(57) **CLAIM**

The ornamental design for a container holder and handle article, as shown and described.

DESCRIPTION

FIG. 1 is an isometric top front view of a container holder and handle article showing our new design;

FIG. 2 is an isometric bottom rear view of the article of FIG. 1;

FIG. 3 is a top plan view of the article of FIG. 1;

FIG. 4 is a bottom plan view of the article of FIG. 1;

FIG. 5 is a left side view of the article of FIG. 1;

FIG. 6 is a right side view of the article of FIG. 1;

FIG. 7 is a front side view of the article of FIG. 1;

FIG. 8 is a back side view of the article of FIG. 1;

FIG. 9 is an isometric top front view of a container holder and handle article showing a second embodiment of our new design;

FIG. 10 is an isometric bottom rear view of the article of FIG. 9;

FIG. 11 is a top plan view of the article of FIG. 9;

FIG. 12 is a bottom plan view of the article of FIG. 9;

FIG. 13 is a left side view of the article of FIG. 9;

FIG. 14 is a right side view of the article of FIG. 9;

FIG. 15 is a front side view of the article of FIG. 9; and,

FIG. 16 is a back side view of the article of FIG. 9.
